UNITED STATES PATENT OFFICE.

EDITH M. WILLEY, OF SEATTLE, WASHINGTON.

STUFFED FIGURE TOY.

Application filed July 13, 1926. Serial No. 122,224.

This invention relates to a figure toy wherein the body is composed of fabric like material adapted to be stuffed, while the limbs are made up of similar material, but 5 remain flat so that they may be readily folded around the body to provide a compact package when the toy is not in use.

The invention is illustrated in the accompanying drawings, in which:—

10 Fig. 1 is a view in elevation of the toy shown in one representation thereof.

Fig. 2 is a transverse section through the body.

15 Fig. 3 is a transverse section through one of the limbs.

The improved toy is made up of a body 1 which in the present instance is egg shaped, representing Humpty-Dumpty, though obviously may be made up in any desired 20 representation.

The body is composed of two or more sections 2 and 3, the fabric being preferably of a more or less waterproof character, such as oilcloth. These sections are united at 25 their edges, there being preferably interposed between such edges a double fold of extra material 4 the fold being disposed outwardly to thus prevent any opening between the stitches. The sections of the body are 30 united except for an opening through which the body is stuffed to the desired shape by any soft flexible material 5, as cotton or the like, it being understood of course that the surface of the body when completed may be 35 painted to represent the object, for example having painted thereon in the present instance the representation of an elongated face.

40 The arms 6 and legs 7 are made up of material similar to that of the body, preferably

in two sections cut of proper outline and united at their edges in a manner similar to that described in connection with the body, or simply stitched together as may be preferred.

45

A particular feature of the present invention is that these arms and legs remain flat, that is, are not stuffed or otherwise filled, so that they are completely flexible and not only add to the flexibility of the figure as a whole, permitting various grotesque positions of such, but have the additional function that they may be readily folded about the body 1 when it is desired to pack the body for storage, or when the same is temporarily not in 50 use. The toy as a whole is designed for the use of children, and may be made in various characteristic representations, and owing to the fact that it is comparatively soft, will not tend to mar furniture or break ornaments when tossed about in play by children, and the complete flexibility of the limbs adds materially to the art positions assumed by such parts.

55

What is claimed is:—

60

A figure toy comprising a hollow elongated substantially egg shape casing adapted to be distended by stuffing and representing the body and face of the figure, arms secured to the upper portion of the casing, and legs 70 secured to the lower portion of the casing, said arms and legs being made up of two sections of material having their edges turned inwardly and stitched, the turned in edge portions forming means to space the 75 sections a slight distance apart while maintaining them comparatively flat and completely flexible as compared with the body.

In testimony whereof I affix my signature.

EDITH M. WILLEY.
